UNITED STATES PATENT OFFICE.

EUGENE SEHL, OF ST. LOUIS, MISSOURI, ASSIGNOR TO HAMILTON, BROWN SHOE COMPANY, OF ST. LOUIS, MISSOURI, A CORPORATION OF MISSOURI.

SHOE-SOLE TRIMMER.

Application filed April 18, 1927. Serial No. 184,766.

This invention relates to shoe sole trimmers, one of the objects being to produce a device whereby marginal portions of shoe soles can be easily, quickly and accurately 5 trimmed to the desired contour.

Prior to this invention, the heel portions of shoe soles have been generally carefully trimmed by hand, and even though skilled operators are employed, the work is both 10 difficult and expensive. My object is to minimize the labor and expense, and also to perform this work with a high degree of accuracy not obtainable from the hand operations.

15 Owing to the irregular contour of a shoe sole, the problem of devising a machine to accurately trim the heel portion involves the difficulty of properly positioning the sole to receive the cutting edge, and I have shown 20 how the desired result can be accomplished by using a gage to locate the toe portion in a predetermined position relative to the cutting edge. More specifically stated, the invention includes a trimming element having 25 a cutting edge conforming to the contour desired at the heel portion of a sole, and a gage contacting with the irregular sole to properly position it with respect to the cutting edge. A further object is to provide 30 a device of this kind adapted to receive both right and left soles.

Another object of the invention is to produce an adjustable device to receive soles of different lengths and shapes, and I have also 35 provided indicating elements to show the size and style for which the machine is adjusted.

A further object is to produce a device 40 adapted to trim the heel portion of a sole having a long tongue to cover the breast of a shoe heel, the tongue being displaced during the trimming operation, so as to lie entirely beyond the cutting edge. After the heel portions have been trimmed by this machine, they may be skived by another machine or in any other suitable manner.

With the foregoing and other objects in view, the invention comprises the novel construction, combination and arrangement of 50 parts hereinafter more specifically described and illustrated in the accompanying drawings, wherein is shown the preferred embodiment of the invention. However, it is to be understood that the invention comprehends changes, variations and modifications

which come within the scope of the claims hereunto appended.

Fig. 1 is a side elevation of a machine embodying the features of this invention.

Fig. 2 is a top view on a larger scale showing the table on which the sole is positioned to receive the trimming element. 60

Fig. 3 is a front elevation of the table, some of the parts being in section, and the trimming element being shown above the 65 table.

Fig. 4 is a section on the line 4—4 in Fig. 2, with the sole omitted and the cutting element added.

Fig. 5 is a section on the line 5—5 in 70 Fig. 2.

Fig. 6 is a perspective view of the toe gage, showing the grooves in its bottom face.

Fig. 7 is a section on the line 7—7 in Fig. 3, showing the holder in which the 75 trimming element is clamped.

Fig. 8 is a diagrammatical view showing a sole confined between gage members and the trimming element above the heel portion of the sole. 80

Fig. 9 is a top view of the parts shown in Fig. 8.

To illustrate one form of the invention I have shown a table 1 supported on a member 2 (Fig. 1) slidably mounted in a vertical guide 3 and having a threaded lower end 4 which cooperates with a nut 5 to permit vertical adjustment of the table. The adjustable supporting member 2 is provided with a pin 6 extending into a slot 7 to prevent rotation of the table. 85 90

Figures 2, 8 and 9 show the manner in which a sole D can be positioned between a toe gage E and a heel gage F to receive a cutting element G having an approximately 95 U-shaped cutting edge adapted to contact with the heel portion of the sole as indicated by the dot and dash line G' in Fig. 2, so as to remove the marginal portion outside of said line. 100

The toe gage E is mounted on a plate 8 slidably fitted to a guide 9 on the table 1, said guide having side members 10 (Fig. 5) with beveled inner faces to receive the correspondingly beveled side edges of the 105 plate 8. The plate 8 can be adjusted in the guide 9 to move the toe gage E toward and away from the heel gage F, and after the desired adjustment has been made, the plate 8 can be secured by means of a locking bar 110

11 (Figures 2 and 3) beveled at one end to engage the plate 8 and having a downturned extension 12 at the other end which rests upon the table 1. This table is threaded to receive a screw 13 (Fig. 3) which passes through the locking bar 11 and has a head 14 contacting with the top of the bar to force the beveled end of said bar onto one of the beveled side edges of the plate 8.

10 The guide 9 is recessed at 15 (Fig. 2) to receive the locking bar 11.

The means for shifting the slidable plate 8 to adjust the toe gage E comprises an operating handle 16 pivoted at 17 (Figures 2 and 3) and provided with an arm 18 having a slot 19 to receive a screw 20 carried by the plate 8, as shown most clearly in Fig. 5. The screw 20 is connected to the slidable plate 8 through the medium of a tube 21 which is 20 threaded to receive the screw 20 as well as a screw 22 whereby said tube is attached to the plate 8. The table 1 and the guide 9 are slotted as shown at 23 and 24 in Figures 2 and 4 to form an elongated passageway 25 for the tube 21.

The heel gage F comprises diverging abutments 25 to receive the heel portion of the sole as shown in Figures 2 and 9, and these abutments extend from a plate 26 slidably mounted in a guide 27 at the rear of the table 1. A spring 28 (Fig. 2), secured by a screw 29, has a free end engaging a lug 30 on the plate 26 and this spring forces the heel gage toward the toe gage. The pressure of the spring is very slight, so the operator can easily position the sole by first placing its heel portion in contact with the diverging faces of the heel gage, and then forcing the sole and heel gage rearwardly 40 before arranging the toe portion of the sole at the toe gage E. The operator can thus quickly arrange a sole in the machine, and when so positioned it is held by the pressure of the spring 28 which forces the heel gage toward the toe gage. The diverging abutments 25 on the heel gage aid in positioning the heel portion.

The trimming element G comprises a die having a U-shaped blade and the dovetail 50 31 above the blade (Figs. 3 and 4) adapted to be clamped between jaws 33 at the lower end of a vertical rod 34. In Figures 3 and 7, a screw 35 is shown to force these jaws toward each other. The trimming element G is 55 thus removably secured to the machine, and in actual practice it is convenient to use trimming elements of different dimensions for the purpose of trimming soles of different shapes and sizes. One trimming element 60 can be easily substituted for another, and certain other devices can be adjusted as will be hereafter described to provide for the trimming of the different soles.

The means for transmitting power to the 65 rod 34 for the purpose of forcing the trim-

ming element onto the sole is shown in Figure 1. This means comprises a lever 36 extending through the rod 34, said lever being fulcrumed at 37. An eccentric 37 is secured to an operating shaft 38 at the lower portion of the machine, and a circular strap, or band 39 surrounds this eccentric 40 designates a rod connecting the strap 39 to the lever 36, as shown in Fig. 1. A spring 41, surrounding the rod 34, engages a washer 42 at the top of the rod, and tends to hold said rod in its elevated position.

To prevent undue injury to the cutting edge at the bottom of the trimming element G, a plate 43 is removably mounted in a holder 44 below the trimming element. (Figures 2 and 4.)

The means for releasing the sole from the U-shaped trimming element comprises a stripper 45 pivotally mounted on a rod 46, and a spring 47 (Fig. 2) engaging the stripper and tending to force its free end onto the yieldable sheet 43. One end of the spring 47 engages the stripper 45, and the other end is secured to the rod 46.

The plate 8 which carries the toe gage E is adjustable in the guide 9, as previously pointed out, and this plate is recessed as shown at 48 in Figures 2 and 4 to receive a stationary member 49 having an inclined top face which deflects the heel portion of the sole upwardly during the operation of placing this heel portion in contact with the heel gage F. In other words, this inclined top face prevents the rear edge of the sole from striking the holder 44 in which the plate 43 is mounted.

When the plate 8 is adjusted to move the toe gage E toward or away from the heel gage F, motion is transmitted to a pointer 50 (Fig. 2) moved along a graduated segment 51 to indicate the sizes of the soles. This pointer is pivoted at 52 and provided with an arm 53 having a slot 54 to receive a screw 55 carried by the slidable plate 8 to which the toe gage is secured. To adjust the machine for a sole of any given length the operating handle 16 (Fig. 2) is adjusted to shift the slidable plate 8 until the pointer 50 is located at the desired indicating point on the segment 51.

The toe gage E is also adjustable to receive soles of different sizes and styles. Each edge of the toe gage (Figures 2 and 6) is provided with a pair of oppositely disposed curved abutments 56 to receive the toes of right and left soles, and this plate also has suitable designations referring to the respective pairs of abutments. For example, the characters B 166 C are shown in Fig. 2 near one edge of the plate to show that this edge is to be used for the B and C widths of shoes known by the number 166. Each edge of this plate is provided with similar indicating characters, and either

edge can be presented toward the heel gage to locate any selected pair of the abutments 56 in its toe-receiving position. To secure the toe gage in either of these four positions, 5 a bar 57 (Figures 2, 3, 4 and 5) is rigidly secured to the slidable plate 8 by means of screws which appear in Fig. 4, and the bottom of the toe gage E is recessed as shown most clearly at 58 in Fig. 6. Each of the 10 recesses 58 is adapted to receive the bar 57 and the toe gage can be thus interlocked with the slidable plate 8. As a further aid in the work of positioning the toe gage it is provided with holes 59 (Figures 2 and 6) to receive a pin 60 carried by the bar 57. When either of the relatively long edges of the gage is in service, the pin 60 lies in the central hole 59, but when either of the shorter edges of this gage is to be used the pin 60 is 15 located in the hole 59 nearest to the selected edge.

It will now be understood that the toe gage is removably interlocked with the slid- 20 able plate 8, and that the gage itself can be 25 adjusted relative to said plate, so as to re- ceive soles of different styles and dimensions. In either case, when the gage is adjusted to the desired position, the plate 8 can be shifted to locate the pointer 50 (Fig. 2) in the 30 position wherein it indicates the length of the sole to be inserted into the machine.

Attention is also directed to the fact that the curved abutments 56 are designed to receive right and left soles, and the abutments 35 of each pair are symmetrical with each other, but they are offset relatively to the heel gage F. This is of course due to the fact that the soles are offset relative to the heels, and one abutment 56 offset in one direction to re- 40 ceive a left sole, while the other is offset in the other direction to receive a right sole.

The sole D shown by Figures 2, 8, and 9 is provided with a tongue 61 integrally united with the body of the sole and adapted to 45 serve as a cover for the breast of the heel of the shoe. However, this tongue is long enough to extend over the heel portion of the sole, and I desire to trim this heel portion without cutting the tongue. With this 50 object in view the operator while placing the sole in the machine, folds the tongue 61 backwardly as shown most clearly in Fig. 8. The tongue is then held by the rod 46 which separates it from the course of the 55 trimming element. In the structure I have shown, the tongue contacts with the upper end of the stripper 45 which surrounds the rod 46.

I claim:

60 1. In a device for trimming the heel por- tions of shoe soles, a trimming element hav- 65 ing a cutting edge conforming to the desired heel portion, and means for locating the toe portion of the sole in a predetermined offset position relative to said cutting edge, said

means including a toe gage to receive the toe portion of the sole, and a heel gage adapted to contact with the heel portion, said toe gage having a face to engage the tip of the toe portion and an extended toe-re- 70 ceiving abutment offset relative to said heel gage to limit the lateral displacement of said toe portion.

2. In a device for trimming the heel por- 75 tions of shoe soles, a trimming element hav- ing a cutting edge conforming to the de- 80 sired heel portion, and means for stopping the toe portion of the sole in a predeter- mined offset position relative to said cutting edge, said means including a toe gage having 85 a pair of oppositely disposed extended abut- 90 ments projecting from a face of said gage and limiting lateral displacement of the toes of right and left soles.

3. In a device for trimming the heel por- 85 tions of shoe soles, a trimming element hav- 90 ing a cutting edge conforming to the desired heel portion, and means for stopping the toe portion of the sole in a predetermined offset position relative to said cutting edge, 95 said means including a toe gage having a pair of oppositely disposed extended abut- 100 ments projecting from a face of said gage and limiting lateral displacement of the toes of right and left soles, and said abutments 105 being symmetrical with respect to said cutting edge.

4. In a device for trimming the heel por- 100 tions of shoe soles, a trimming element hav- 105 ing a cutting edge conforming to the desired heel portion, and means for locating the toe portion of the sole in a predetermined position relative to said cutting edge, said means including a toe gage having an abut- 110 ment to receive the toe portion of the sole, a heel gage adapted to contact with the heel portion to be trimmed, and means whereby 115 said heel gage is yieldingly forced toward said toe gage.

5. In a device for trimming the heel por- 110 tions of shoe soles, a trimming die having an 115 approximately U-shaped cutting edge, and means for locating the shoe sole in a pre- 120 determined position relative to said cutting edge, said means including a toe gage having oppositely disposed abutments to receive the toes of right and left soles, a heel gage 125 adapted to contact with the heel portions of the soles, means whereby said heel gage is yieldingly forced toward said toe gage, said toe gage being adjustable toward and away from said heel gage, and an indicator 130 cooperating with said toe gage to indicate the length of the sole.

6. In a device for trimming the heel por- 125 tions of shoe soles, a trimming die having an approximately U-shaped cutting edge, and means for locating the shoe sole in a pre- 130 determined position relative to said cutting edge, said means including a toe

gage having oppositely disposed curved abutments to receive the toes of right and left soles, a heel gage having diverging abutments to receive the heel portions of the soles, a spring whereby said heel gage is forced toward said toe gage, a slide on which said toe gage is mounted, an operating handle cooperating with said slide to adjust said toe gage toward and away from said heel gage, and an indicator cooperating with said slide to indicate the length of the sole.

7. In a shoe sole trimmer, a trimming element having a cutting edge, and means for locating the toes of shoe soles in predetermined positions relative to said cutting edge, said means including a toe gage having pairs of oppositely disposed abutments to receive the toes of different right and left soles, and means for securing said gage in different positions to locate a selected pair of abutments in its toe-receiving position.

8. In a device for trimming the heel portions of shoe soles, a trimming element having a cutting edge conforming to the desired heel portion, and means for locating the toe portion of the sole in a predetermined position relative to said cutting edge, said means including a plate having a plurality of edges, each edge being provided with a pair of oppositely disposed abutments to receive the toes of right and left soles, said plate also having designations referring to the respective pairs of abutments, and means for securing said plate in different positions to locate a selected pair of abutments in its toe-receiving position.

9. In a device for trimming the heel portions of shoe soles having tongues adapted to extend over the heel portions, a movable trimming die having a cutting edge conforming to the desired heel portions, and a tongue-holding member whereby the tongues are separated from the course of the die.

10. In a shoe sole trimmer, a gage to locate the toe end of the sole, a heel gage to contact with the heel edge of the sole, said heel gage being yieldable to compensate for variations in the lengths of the soles to be trimmed, and a heel-trimming device operating between said gages, said device being in front of and adjacent to said heel gage, said heel-trimming device having a cutting edge conforming to the desired shape of the heel edge, so as to remove the margin in contact with said yieldable heel gage.

11. In a shoe sole trimmer, a toe gage to contact with the toe end of the sole, a heel gage to contact the heel end, and a heel-trimming device operating between said gage members, said trimming device having a contour conforming to the desired shape of the heel edge, so as to remove the margin in contact with said heel gage, said heel gage being yieldable to compensate for variations in the soles to be trimmed, said toe gage being rigidly held in position, and said toe gage being adjustable toward and away from the yieldable heel gage to vary the distance between said toe gage and the cutting edge.

In testimony that I claim the foregoing I hereunto affix my signature.

EUGENE SEHL.
